WALTER K. FOSTER, OF CAMBRIDGEPORT, MASSACHUSETTS.

Letters Patent No. 70,082, dated October 22, 1867.

IMPROVEMENT IN WASHERS FOR AXLE-BOXES.

The Schedule referred to in these Letters Patent and making part of the same.

TO ALL PERSONS TO WHOM THESE PRESENTS MAY COME:

Be it known that I, WALTER K. FOSTER, of Cambridgeport, in the county of Middlesex, and State of Massachusetts, have made a new and useful invention, having reference to Washers for Axle-Boxes and Journals of Wheel-Carriages; and I do hereby declare the same to be fully described in the following specification, and represented in the accompanying drawings, of which—

Figure 1 denotes a longitudinal section of a wheel-box, its washers and journal, as provided with my invention.

Figure 2 a side view, and

Figure 3 a transverse section of one of the journal-washers and its metallic annular guards.

The nature of my invention consists in the combination of one or more annular or flanged rings with each of the leather washers of the axle-journal and its box; there being usually two of such leather washers to each journal. They are situated in manner as represented in fig. 1, in which they are shown at *a* and *b*; *A* being the axle, *B* the wheel-box, and *e* the journal of the axle.

Washers, as commonly employed, have no metallic facings nor guards, as hereinafter described. The consequence is that they soon become compacted and worn out by pressure and friction against them, while the wheel may be in use. In order to gain and preserve all the advantages of the leather washer, I apply against either or each of the sides of the washer an annulus, *c*, of plate metal, which I make with a flange, short tube, or lip *d*, to project from its inner periphery into the washer, and to fit against the inner circumference thereof. I prefer, however, to employ two of such lipped annuli to each washer, they being constructed so that the lip or tube of one may enter that of the other a short distance, when the two annuli are applied to opposite faces of a washer. The lips of the annuli prevent wear of the leather on its inner circumference, by the journal protected, washers will last in a wheel-box a very much greater length of time than they will without the protection. The metallic annuli preserve the normal elasticity and cushioning properties of the leather, and enable it to contract and expand as circumstances may require. I sometimes make each of the guards with two tubes or lips, they being arranged in manner as shown in fig. 4, in which *W* is the washer, *R* *R'* the annuli, and *I* *I'* their tubes or lips. The tubes of one washer overlap those of the other. The guards prevent the ordinary contraction and consequent distension of the washer and its wear on its inner circumference. In this way the guard prevents particles of the washer from getting in contact with the journal, and being mixed with the oil to the detriment of the rubbing surfaces of the journal and its box.

By preventing wear of the washers, by the means explained, I prevent the jamming of the conical journal into its box, so as to cause the two, when the wheel is in revolution, to become heated, and adhere, or be fixed, or "set" together.

What I claim, is—

The combination and arrangement of one or two metallic annuli or guards, or flanged rings, with a leather washer, or its equivalent, arranged within said rings, and to be used on an axle-journal in manner as set forth.

I also claim the flanged guards as made with lips on their inner ends and outer circumferences to receive a washer, as specified.
